US00D510846S

(12) United States Design Patent **(10) Patent No.:** **US D510,846 S**
Hardy **(45) Date of Patent:** **** Oct. 25, 2005**

(54) MODULAR GROWING PLANT SUPPORT SYSTEM

6,385,901 B1 5/2002 Wahlberg
6,389,744 B1 * 5/2002 Pugh 47/47
6,401,385 B1 6/2002 Kleinert
6,490,825 B1 12/2002 Dillon et al.
2002/0029518 A1 3/2002 Peck

(76) Inventor: **Stephen D. Hardy**, 5304 Shriver Ave., Des Moines, IA (US) 50312

(**) Term: **14 Years**

FOREIGN PATENT DOCUMENTS

(21) Appl. No.: **29/203,380**

DE 2801004 A 1/1977
JP 118771 A 7/1999

(22) Filed: **Apr. 13, 2004**

* cited by examiner

(51) LOC (8) Cl. **08-01**

Primary Examiner—Holly Baynham

(52) U.S. Cl. **D8/1**

(74) Attorney, Agent, or Firm—Sturm & Fix LLP

(58) Field of Search **D8/1; 47/47, 43-44, 47/32.4, 32, 30**

CLAIM

(56) References Cited

The ornamental design for a modular growing plant support system, as shown and described.

6,088,956 A	7/2000	Rocka

FIG. 1 is a perspective view of the modular growing plant support system showing my new design;
FIG. 2 is a front elevational view thereof, the rear elevational view being a mirror image thereof;
FIG. 3 is a left side elevational view thereof;
FIG. 4 is a right side elevational view thereof;
FIG. 5 is a top plan view thereof; and,
FIG. 6 is a bottom plan view thereof.
